UNITED STATES PATENT OFFICE.

ROBERT WILLIAM ATKINSON, OF ROCKY RIVER, OHIO.

METHOD OF VENDING COLD CREAM AND THE LIKE.

Application filed June 1, 1926. Serial No. 112,812.

My invention relates to an improved method of vending cold cream and the like for facial applications, and an object of my invention is to provide for the packaging and vending of only a sufficient amount of cold cream or like materials, commonly made of a combination of cleansing agents and including an oil, in an emulsion with water, suitable for a single application to the face 10 of the purchaser of the article.

It has been more commonly prevalent of late than formerly for users of cosmetics, such as cold cream and the like, to employ them frequently, and it is therefore an object 15 of my invention to package a limited supply of such cold cream or like material in such a way that the same may be very easily dispensed from the package in an amount sufficient for one application to the face of the 20 user and without requiring the user to withdraw such a limited quantity as is required at the time from a larger mass of cream, which is inconvenient, and it is likewise inconvenient to carry such a larger quantity 25 of the material.

Another object of my invention, therefore, is to provide a new method of vending cold cream and like materials in limited quantities without waste.

Other objects of my invention and the invention itself will be revealed as the description of an embodiment thereof progresses, and in which description reference will be had to the accompanying drawings illustrating the principles involved.

Referring to the drawings:

Fig. 1 shows in longitudinal medial section the packaged material to be vended;

Fig. 2 illustrates the package separated 40 into its two telescopic parts;

Fig. 3 illustrates a preliminary step in the ejecting of cold cream from the reservoir 1 of the containing parts of Fig. 2;

Fig. 4 illustrates a subsequent stage in the 45 operation;

Fig. 5 illustrates a succeeding stage and Fig. 6 illustrates the ultimate stage in the operation;

Fig. 7 illustrates a stage of improper operation which would be secured were it not for certain provisions, hereinafter set forth, had in the enjoyment of my invention; and

Figs. 8 and 9 illustrate subsequent stages 50 in the operation which would be secured if the invention were attempted to be practiced

under the improper conditions hereinafter set forth and referred to hereinabove in connection with Fig. 7.

In the practice of my invention, I employ a capsule comprising two parts, one of the 60 parts illustrated at 1 being a cold cream reservoir and a second part 2 being a cap adapted to be telescoped over the mouth of the reservoir part to close the same, as illustrated in Fig. 1. Both the reservoir 65 and the cap are generally in cylindrical form with rounded ends and circular mouths. The diameter of the cylindrical portion of the cap is sufficiently greater than the diameter of the cylindrical portion of the reservoir, so that the cap may be telescoped over 70 the exterior of the reservoir but making a snug fitting contact therewith. The capsule reservoir portion 1 is preferably made of gelatin material; the cap 2 may likewise be 75 made of gelatin material but it may also be made of other materials, such as celluloid and the like.

In the practice of my improved method, I first provide an emulsion of cold cream 80 material constituents comprising an oil and water, the amount of oil and water being preferably such as to secure good cleansing qualities, and at the same time the amount of water in the material is made sufficient 85 in quantity that coming in contact with the gelatin material 1, in about a week's time, it will so soften the gelatin material that the container 1 having a rounded dome shaped end 3 may be taken between the 90 fingers of one hand, as illustrated in Fig. 3, and upon pressure being exerted by the fingers toward each other, the container will be deformed, as illustrated in Figs. 4, 5 and 6, successively, Fig. 6 representing a stage 95 wherein the capsule will be entirely flattened out.

In Figs. 7, 8 and 9, I have illustrated what takes place in a capsule of the ordinary gelatin type when filled with a cream material 100 not containing an emulsion comprising water, or wherein the water has not been permitted to soften the capsule to permit its dome portion 3 to be flattened by a pressure exerted by the fingers of one hand, or 105 wherein a container of other material than gelatin, such as a celluloid container, is employed. In all such latter cases, it is practically impossible with the amount of pressure which could conveniently be exerted 110

by a person of ordinary strength to flatten containers heretofore in common use in order to dispense substantially the entire contents of the container. The dome 3 being an arch, is required to be softened to make it pliable, in order that it may be crushed or flattened, as illustrated in Fig. 6, and only under such flattening conditions may the contents of the container be ejected economically, since otherwise there will always reside in the container a major portion of the cold cream material.

By so packaging the cold cream material, users may carry one or more of the capsules with them in a purse, vanity case, pocket, or the like, and after expressing the contents, can throw away the container, it being inexpensive and purchasably filled with cold cream at small cost.

After packaging the cold cream material, as illustrated in Fig. 1, I preferably dip the capsule, after closing it, into an oil, which will enter between the contacting surfaces of the capsule end 2 and the capsule end 1 and seal the interior of the capsule and prevent its moisture content from being changed by leakage through the joint formed by the contacting portions of the two telescoped capsule parts. The capsules are then ready for marketing, and I may enclose each of them in a wrapper of non-absorbent material, such as waxed paper, cellophane or the like.

In order to prevent an undue softening of

the capsule material when the cold cream material packaged comprises such an amount of water as would otherwise unduly soften the capsule, sometimes I previously expose the capsule to the fumes of formaldehyde. I find that when this is done that the capsule is made more or less non-absorbent, depending upon the amount of exposure to the fumes, and by predetermining the amount of exposure a predetermined amount of softening may be accomplished.

Having thus described my invention in this specific embodiment, I am aware that the same may be embodied in containers of different materials and form, and for vending substances, departing from that herein specifically described but all without departing from the spirit of my invention.

I claim:

A container adapted to hold cold cream comprising an emulsion of oil and water, comprising a pair of gelatin capsule cups, one of which has a dome-shaped closed end, both having open ends, the open end of one of the cups being of less diameter than that of the other cup and adapted to be telescoped therein, the walls of the container adapted to be acted upon by the water in the emulsion to soften the same, the outer surface of the walls being rendered hard and relatively non-absorbent of water.

In testimony whereof I hereunto affix my signature this 6th day of May, 1926.

ROBERT WILLIAM ATKINSON.
